INVENTOR

BY

H. G. Burns ATTORNEY

UNITED STATES PATENT OFFICE.

EPHRAIM R. NABLO, OF FORT WAYNE, INDIANA.

HOSE SUPPORTER.

Application filed June 13, 1924. Serial No. 719,730.

To all whom it may concern:

Be it known that I, EPHRAIM R. NABLO, a citizen of the United States of America, and resident of Fort Wayne, in the county of Allen and State of Indiana, have invented certain new and useful Improvements in Hose Supporters, of which the following is a specification.

This invention relates to improvements in clasps for hose supporters particularly for use in making a detachable connection between a supporter strap and the hose, and the object of the improvement is to provide a detachable clasp applicable to hosiery which may be readily applied and removed from the hose without injury to the fabric. Another object of the invention is to provide in a hosiery clasp a pliant stud upon which the fabric is clamped so constructed as to increase its pressure upon the fabric and thus hold the hose with greater firmness as the tension between the hose and the hose supporter is increased.

These objects are accomplished by the construction illustrated in the accompanying drawings, in which:

Fig. 1 is a front elevation of a clasp embodying the invention, the clamp being shown closed;

Fig. 2 is a similar view showing the clamp open;

Fig. 3 is a side view in central section with the clamp and the swinging stud in open position;

Fig. 4 is a rear elevation of the supporting frame for the parts;

Fig. 5 is a rear elevation of the stud support;

Fig. 6 is a cross section of Fig. 5 on the line 6—6 thereof; and

Fig. 7 is a side elevation of the clasp connected with a supporter strap.

The characters appearing in the description refer to parts shown in the drawings and designated thereon by corresponding characters.

The invention consists of a supporting frame 1 formed of a metallic plate and shaped with an inturned wing 2 at each side thereof to form a corresponding longitudinal guide-way 3, the lower end of the plate being upturned to form a rounded jaw 4. The frame has a central opening 5 therein between the side wings 2, and at the upper end of the opening is a hinge lug 6 formed by curling an integral part of the plate up-

wardly, there being a similar lug 7 formed at the lower end of the opening. In the upper end of the frame are made a pair of laterally disposed slots 8 for the accommodation of a supporter strap 9 to which the clasp is secured. A shackle 10 consisting of an elongated wire loop having parallel sides 11, is mounted in the frame and has longitudinal movement therein, its respective sides 11 being positioned in the corresponding guideways 3 and extending also in the corresponding end of the jaw 4 which is made narrow at the bottom to admit of the passage of the loop sides 11 and form an additional guide therefor. On the upper end of the shackle 10 is hinged a lever 12 which is connected also with the hinge lug 7 by a fulcrum link 13, there being a hinge lug 14 on the lever in which the upper end of the link 13 is secured. The opening 5 in the frame admits of the movements of the lever and the link through the front thereof and the lever is so shaped as to close said opening when the lever is in its lowermost position. The free end 15 of the lever is arched outwardly and has lateral ears 16 that extend over and clasp the corresponding sides of the frame when the lever is in its lowermost position.

An arm 17 formed of spring wire is secured at one of its ends in the hinge lug 6 at the back of the frame, and at its opposite end is fixed a base plate 18 having a lateral slot 19 therein for the accommodation of the lower end of the strap 9. The extreme lower end of the arm 17 is bent at right angles and projects through the base plate 18 affording a mount or projecting loop 20 upon which is positioned a rubber stud 21. A yoke plate 22, the middle portion of which extends down into the stud and through the loop 20 and the ends of which are spread out oppositely over the top of the stud limits the endwise expansion of the rubber stud, and also admits of the stud being compressed endwise. When the arm 17 is swung upon its hinged connection the stud is swung into or out of the opening in the shackle 10 beneath the jaw 4 when the shackle is moved downwardly to admit of the insertion or withdrawal of the stud.

The clasp is secured to a supporter strap 9 that depends in the ordinary manner from a corset or other garment (not shown), the strap passing successively through the openings 8 in the frame and its lower end being

looped through the opening 19 in the base-plate 18, the strap serving also as a cover for the back of the arm 17.

In utilizing the invention the lever 12 is raised by applying the finger to the arched end 15 thereof or by grasping the ears 16 between the thumb and finger and swinging the lever outwardly. The lever turns upon its connection with the link 13 as a fulcrum so that the shackle attached to the inner end of the lever is moved downwardly in its guides. The arm 17 is swung backwardly together with the stud sufficiently to admit of inserting the top of the hose (not shown) between the arm and the frame as in applying the ordinary clasp. The arm is then pressed toward the frame until the stud is forced beneath the jaw 4 and into the shackle with the adjacent portion of the 20 hose extending over the stud where it is secured by returning the lever to its closed position which causes the shackle to be drawn upwardly and clamp the hose covered stud against the jaw of the frame. While the hose is thus secured and tension is applied thereto, that portion of the hose covering the outer end of the stud is drawn tightly thereover which tends to compress the stud endwise. As the stud is thus compressed endwise, it expands accordingly with corresponding force toward the jaw and the surrounding shackle clamping the intervening portions of the hose with increased firmness without unduly crushing and thus injuring the fabric of the hose.

What I claim is:—

1. In a garment clasp, an apertured frame having a longitudinal guide-way in each side thereof, a jaw at its lower end and a hinge lug at the top and bottom of its aperture; a shackle loop longitudinally movable in said guide-ways and encompassing the jaw; an operating lever extending through the aperture of the frame and hinged on the upper end of the loop; a fulcrum link for the lever pivoted in the lowermost hinge lug; a swinging arm connected at its upper end in the uppermost hinge lug; a base plate on the arm, the lower end of the arm extending through said plate affording a projecting loop; a rubber stud secured by said projecting loop to said plate; a yoke plate the middle portion of which extends down into the stud and through said projecting loop and the ends of which spread out oppositely over the top of the stud; and a supporter strap connected to the upper end of the frame and the lower end of the base plate and covering the back of the arm.

2. In a garment clasp, an apertured frame 60 having a longitudinal guide-way in each side thereof and a hinge lug at the top and bottom of its aperture; a swinging arm connected at its upper end to the uppermost hinge lug; a rubber stud in connection with the lower end of the arm and having bearing contact against the lower end of the frame; a shackle loop longitudinally movable in said guideways and encompassing the stud; a toggle mechanism connected with the frame and the shackle operable to move the shackle into binding engagement with the stud; and a supporter strap connected with the frame and covering the back of the arm. 65

3. In a garment clasp, a frame having longitudinal guide-ways therein; a rubber stud member including an arm hinged at the upper part of the frame, the rubber stud having bearing contact upwardly against the lower end of the frame; a shackle loop longitudinally movable in the guideways and encompassing the stud; and a toggle mechanism connected with the frame and the shackle upwardly operable to move the shackle into binding engagement with the 70 stud. 75

4. In a garment clasp, a frame having a longitudinally disposed guide-way in each 80 side thereof and an opening in its front; a rubber stud member including an arm hinged at the back of the frame in the upper part thereof, the stud being engageable against the lower end of the frame; a shackle loop, having sides which are movable longitudinally in the guide-ways of the frame 85 respectively, the lower end of the loop extending beneath said rubber stud and operable to bind the stud against the adjacent end of the frame; a fulcrum link hinged to the frame at the lower end of the opening and being movable between the sides of the shackle; and a lever having hinged connection with the top of the shackle and with the top of the link, and being operable to actuate the shackle and close the opening in the 90 frame. 95

5. In a garment clasp including a frame and movable shackle member, a swinging arm attached at one end of the frame and having a mount on its other end; a compressible rubber stud on the mount and engageable in the shackle member; and a yoke in connection with the mount, engaging the outer end of the stud and operable to limit the endwise expansion of the stud. 100 110

In testimony whereof I affix my signature.

EPHRAIM R. NABLO.
